Primary Examiner — Carol P Rademaker(74) *Attorney, Agent, or Firm* — Melissa G. Krasovec; Leonard W Lewis(57) **CLAIM**

The ornamental design for a bottle, as shown and described.

DESCRIPTION

FIG. 1 is an isometric view of the bottle of the claimed design; FIG. 2 is a front elevational view thereof; FIG. 3 is a back elevational view thereof; FIG. 4 is a left side elevational view thereof; FIG. 5 is a right side elevational view thereof; and, FIG. 6 is a top plan view thereof; and, FIG. 7 is a bottom plan view thereof.

The broken lines showing a closure and a portion of the bottom surface are included for the purpose of illustrating environmental structure and form no part of the claimed design.
